UNITED STATES PATENT OFFICE.

ANDREW E. ROBSON, OF PITTSBURG, PENNSYLVANIA.

DESIGN FOR A GRAINING-TOOL.

SPECIFICATION forming part of Design No. 31,439, dated August 22, 1899.

Application filed July 12, 1899. Serial No. 723,623. Term of patent 7 years.

To all whom it may concern:

Be it known that I, ANDREW E. ROBSON, a citizen of the United States of America, residing at Pittsburg, in the county of Allegheny and State of Pennsylvania, have invented a certain new and useful Design in Graining-Tools, of which the following is a specification, reference being had therein to the accompanying drawings.

- 10 This invention relates to certain new and useful designs in graining-tools, and has for its object to design a tool of the above-described class that will be highly ornamental in appearance.
- 15 The invention consists in the novel form and outline of the tool to be hereinafter more particularly described, and specifically pointed out in the claim.

Referring to the drawings, Figure 1 is a perspective view of my new grainer's tool. Fig. 2 is a side elevation of the same. Fig. 3 is a vertical sectional view taken on the line 3 3 of Fig. 2.

Referring to the drawings by reference-numerals, 1 indicates the body portion of the tool, which is substantially wedge-shaped in cross-section, the said body portion being formed with converging sides 2, and the upper ridge of the body portion has formed therein V-shaped notches 3, forming between them projections 4. The sides and upper end terminate in a rounded portion 5.

Having fully described my invention, what I claim as new, and desire to secure by Letters Patent, is—

The design in a graining-tool, substantially as herein shown and described.

In testimony whereof I affix my signature in the presence of two witnesses.

ANDREW E. ROBSON.

Witnesses:

JOHN NOLAND,
E. W. ARTHUR.
